UNITED STATES PATENT OFFICE.

STANLEY ANTHONY, OF BOSTON, MASSACHUSETTS.

HAND-BAG.

1,319,134.

Specification of Letters Patent. Patented Oct. 21, 1919.

Application filed April 25, 1918. Serial No. 230,616.

To all whom it may concern:

Be it known that I, STANLEY ANTHONY, a citizen of the United States, residing at Boston, county of Suffolk, State of Massachusetts, have invented an Improvement in Hand-Bags, of which the following description, in connection with the accompanying drawing, is a specification, like characters on the drawing representing like parts.

This invention relates to hand bags such as are commonly used for school or business purposes, and it has for its object to provide an improved frame construction for the bag which is simple and inexpensive to manufacture; which is strong, and which has other advantages that will be more fully hereinafter set forth.

In order to give an understanding of my invention, I have illustrated in the drawings a selected embodiment thereof which will now be described, after which the novel features thereof will be pointed out in the appended claims.

Figure 1 is a view of a hand bag embodying my invention;

Fig. 2 is a view of one of the frame members before it is bent into shape;

Figs. 3 and 4 are perspective sectional views of one of the frame members showing the manner in which the side and lining of the back are fastened thereto;

Fig. 5 is an enlarged section on the line 5—5, Fig. 1;

Fig. 6 is a side view of one of the frame members after it is bent into shape;

Fig. 7 is a section on the line 7—7, Fig. 5;

Fig. 8 is an end view of the bag.

My invention is adaptable for use in the manufacture of hand bags of various types. I have chosen to illustrate it as it would be used in the manufacture of a hand bag of the type commonly known to the trade as the Boston bag. The so-called Boston bag has the general shape shown in Fig. 1, it comprising a body portion 1 open at the top and having a U-shaped handle 2 secured to each side adjacent the top, the bag being held closed by means of a strap 3 secured to one side which buckles into a buckle 4 secured to the other side. In bags of this type it is common to attach the two sides of the bag to so-called frame members which are pivoted together and which constitute the frame of the bag. The present invention relates particularly to the manner of constructing these frame members.

Each frame member of the bag is made

from a strip of sheet metal 5, such as shown in Fig. 2, which is first folded or bent longitudinally along substantially the dotted line 6, so as to present a U-shape in cross-section with one leg of the U longer than the other. This is shown in Figs. 3 and 4 wherein the strip 5 has been bent so that it presents the long leg 7 and the short leg 8. After the strip has been thus formed, the edges 9 and 10 of the lining 11 and body material 12 of the bag are inserted into the U-shaped strip, as shown in Fig. 3 with the lining 11 against the longer leg 7 and the face 13 of the body material that is to constitute the outer face of the bag against the shorter leg 8. The lining and body material are inserted into the metal strip while it is straight and before it has been bent transversely into the shape which it has when incorporated into the bag. After the frame member 5 has been thus applied to the edge of the lining 11 and body material 12, said body material is folded around the shorter leg 8 and over the longer leg 7 of the frame member so as to overlie the opposite face of the lining 11 from that with which it contacts in Fig. 3. This operation of folding the body material around the frame member 5 brings the face 13 of the body material on the outside, and it also results in providing a covering of the material 12 for the frame member 5. After the body material 12 has thus been folded about the frame member, as shown in Fig. 4, then the body material and lining are stitched together by a line of stitches 14 which extend along the edge of the longer leg 7 of the frame member. This stitching is accomplished while the frame member 5 is still in the form of a straight strip and because of this fact the stitching can be readily done in any ordinary sewing machine. After the stitching 14 has been completed, then the frame member 5 is bent transversely into the U-shape required for the shape of the bag, as seen in Fig. 6. Both frame members will be made in the same way and after they have been sewed to the lining and body material 12 of the bag and bent into the U-shape shown in Fig. 6 they are suitably pivoted together at their ends, as shown at 26. The two frame members will be bent into such shape that when the bag is closed they will have overlapping relation, as shown in Fig. 5, thus making a better closure than if they merely had an abutting relation.

In order to provide an anchorage for the

handles 2, I propose to secure to each frame member two fingers or projections 16 to which the ends 15 of the handles may be secured. These fingers may conveniently be formed from L-shaped brackets 17, one leg 18 of each bracket being riveted to the frame member and the other leg 16 of the bracket depending from the frame member and constituting the anchorage to which the 10 end of the handle may be secured. I propose to secure the legs 18 of each bracket to the portion of the sides 7 of the frame member which projects beyond the leg 8, as clearly seen in Fig. 5, and this may be 15 done by means of rivets 19 or in any other suitable way. The portion 16 of the brackets will thus overlie the inside wall of the lining 11 of the bag, and the ends 15 of the handles may be readily riveted 20 to the depending portion 16 by means of rivets 20. This makes a very firm and secure anchorage for the handles 2. It will be noted that in the construction shown, each frame member is formed from a single strip 25 of metal and the manner of securing the side of the bag thereto is such that the frame members are covered by an integral portion of the body 12 of the bag. Moreover, the operation of attaching the frame members 30 to the bag body is greatly facilitated by reason of the fact that all the sewing necessary is done while the frame members 5 are straight and before they are bent into the U-shape shown in Fig. 6.

35 I claim:

1. In a hand bag, the combination with two frame members pivotally connected together and each having a U-shape in cross-section, of bag sides having their top edges 40 inserted between the sides of the U-shaped frame members, the portions of the bag sides adjacent said edges being wrapped about and constituting a covering for the frame members.

45 2. In a bag, the combination with two frame members pivotally connected together and each having a U-shape cross section, of two bag sides each having a portion thereof inserted between the sides of a frame member and another portion thereof inclosing and constituting a covering for said frame member.

55 3. In a bag, the combination with two frame members pivotally connected together, of two bag sides each having a portion embraced by one of the frame members and another portion inclosing and constituting a covering for said frame member.

60 4. In a bag, the combination with two frame members pivotally connected together, each having a U-shape in cross section, of bag sides comprising body material and lin-

ing material, both body and lining having their top edges inserted between the legs of the U-shaped frame members and the body 65 material embracing and constituting a covering for the frame members.

5. The method of making a hand bag which consists in bending each of two metal strips longitudinally thereby to form two 70 strips U-shaped in cross section with one leg of the U longer than the other, inserting the edges of the body material and lining between the sides of each U-shaped strip, folding the body material around the edge of the 75 shorter leg of the strip and around the body of the strip, sewing the body and lining together adjacent the edge of the longer leg of the strip, bending the two strips transversely with the body and lining material 80 fastened thereto and then pivoting said strips together.

6. The method in making a hand bag which consists in folding the edge of the body material of said bag around straight 85 metallic strips, sewing such body material to said strips while in their straight form, then bending said strips transversely into U-shape and pivoting said strips together.

7. In a hand bag, the combination with two frame members pivotally connected together, of two bag sides secured to said frame members, a pair of L-shaped brackets, each having one leg secured to a frame member and the other leg overlying the inside 95 of the bag side, and handles riveted to said latter legs.

8. In a hand bag, the combination with two frame members pivotally connected together and each having a U-shape in cross 100 section with one leg of the U longer than the other, of bag sides having their edges inserted in the U-shape of the frame members, L-shaped brackets, each having one leg riveted to the longer leg of the frame member, and the other leg overlying the inside 105 of the bag, and handles riveted to said other legs.

9. In a hand bag, the combination with two frame members pivotally connected together, each having a U-shape in cross section, of bag sides comprising body material and lining material, both body material and lining material having a portion inserted between the legs of the U-shaped frame members and the body material embracing and constituting a covering for the frame members, said body material and lining material being secured together along the edge of the frame members.

110 120 In testimony whereof, I have signed my name to this specification.

STANLEY ANTHONY.
